UNITED STATES PATENT OFFICE

CARROL A. LOOK, OF LOS ANGELES, CALIFORNIA

DESIGN FOR A BEVERAGE FAUCET

Application filed February 13, 1931. Serial No. 38,647. Term of patent 3½ years.

To all whom it may concern:

Be it known that I, CARROL A. LOOK, a citizen of the United States, residing at Los Angeles, in the county of Los Angeles and State of California, have invented a new, original, and ornamental Design for Beverage Faucet, of which the following is a specification, reference being had to the accompanying drawings, forming part thereof.

Fig. 1 is a side elevation of a beverage faucet showing my new design.

Fig. 2 is a top plan view thereof.

Fig. 3 is an end elevation of the same.

I claim:

The ornamental design for a beverage faucet, as shown.

C. A. LOOK.
